UNITED STATES PATENT OFFICE.

BURTON W. SIMER AND ANTHONY NICHOLS, OF SALMON, IDAHO.

SELF-CLOSING SACK

1,089,279.

Specification of Letters Patent.

Patented Mar. 3, 1914.

Application filed September 19, 1913. Serial No. 799,736.

To all whom it may concern:

Be it known that we, BURTON W. SIMER and ANTHONY NICHOLS, citizens of the United States, residing at Salmon, in the 5 county of Lemhi and State of Idaho, have invented new and useful Improvements in Self-Closing Sacks, of which the following is a specification.

This invention is an improved sack or bag, 10 adapted for holding cement or other material and which can be closed without sewing and can be readily emptied and refilled, the object of the invention being to provide an improved sack of this character which can 15 be handled, filled or emptied without the necessity of sewing up the same or ripping the same when it is desired to empty the sack, the invention consisting in the construction, combination and arrangement of 20 devices hereinafter described and claimed.

In the accompanying drawing: Figure 1 is a side elevation of a self closing sack constructed in accordance with our invention showing the same opened. Fig. 2 is a similar view, showing the sack closed. Fig. 3 is 25 a plan of the same partly in section. Fig. 4 is a vertical sectional view of the upper portion of the sack.

The sack 1 may be of any suitable size 30 and shape and may be made of any suitable material. It is permanently closed at both ends, and one end 2 which we here call an open end, is formed at one side with a spout 3 which is at one corner of the sack and is 35 adapted to be extended longitudinally therefrom to open the sack and to be folded across the upper end of the sack in order to close the same. This spout is here shown as tapering in form from its base or inner 40 end to its upper or discharge end and is constructed integrally with the sack, all of the upper end of the sack being permanently closed as by means of stitching 4, excepting the mouth 5 of the spout. The upper end 45 of the sack is provided at the side opposite the spout 3 with an eyelet 6. An opening cord 7 is attached to the outer end of the spout, on the outer side of the latter and a closing cord 8 is attached to the opposite 50 side of the mouth of the spout and run down

through one side of the spout, on the inner side thereof, and also across the sack on the inner side thereof, and cut through the eyelet 6. The cord 7 enables the spout to be readily pulled to open position as shown in Fig. 1 when the cord 8 has been loosened and the cord 8 enables the spout to be folded across the upper end of the sack, in order to close the same and may also be used for fastening the sack by being wound around a corner thereof as shown in Fig. 2.

Our improved sack may be readily opened and closed, may be readily filled and emptied, and hence may be reused a number of times thus effecting a considerable economy by lengthening the life of service of the sack and also greatly reducing the labor and saving time in opening and closing the sack.

While we have herein shown and described the preferred form of our invention we would have it understood that changes may be made in the form, proportion and construction of the several parts without departing from the spirit of our invention and within the scope of the appended claims.

Having thus described our invention we claim:

1. A sack closed at both ends and provided at one of its closed ends with a spout adapted to be extended therefrom or to be folded on the same and a closing cord attached to the said spout, the said closing cord being arranged on the inner side of the spout and on the inner side of the sack, extending across the sack and being led out through an opening in one side of the sack.

2. A sack closed at both ends and provided at one of its closed ends with a spout adapted to be extended therefrom or to be folded on the same and a closing cord attached to the said spout, the said closing cord being arranged on the inner side of the spout and on the inner side of the sack, extending across the sack and being led out through an opening in one side of the sack, the sack being provided with an eyelet in the said opening and through which the said cord extends.

3. A sack of the class described closed at both ends and provided at one of its closed

2
ends with an integral, flexible spout arranged at one corner thereof and adapted to be extended therefrom or folded across the same, an opening cord attached to the outer side of the spout at its mouth and a closing cord attached to the inner side of the spout at its mouth.

In testimony whereof we affix our signatures in presence of two witnesses.

BURTON W. SIMER.
ANTHONY NICHOLS.
